UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Original application filed September 27, 1922, Serial No. 590,756. Divided and this application filed July 23, 1925. Serial No. 45,548.

The present invention relates to sound-deadening casings for typewriting machines.

- A casing of this character has an opening in the front thereof, through which the keyboard extension of the machine may project, for access by the operator to the keys thereof. The casing, at its base, is ordinarily of a width conformable to the width of the main frame of the machine; allowance being made 5 for easy placement and removal of the machine; but, above the base, is flared or extended laterally outward to provide space in the upper part thereof, for movement of the typewriter-carriage in letter-feed and re- 10 turn directions; and the upper part of the casing is slotted horizontally and longitudinally thereof, for projection therethrough, and for movement therewith, of the operating levers on the typewriter-carriage. 15 The casing is usually made in two sections, to wit, a body-section, provided with a suitable base-piece, and a cover-section, hinged thereto; the cover being opened for placement and removal of the machine. The 20 opening in the front wall of the casing for the keyboard extension may extend to the top of the casing-body; or may not extend to the top of the casing-body, in which latter event the machine may be inserted into the 25 casing, in tilted position, and the keyboard extension passed forward through the opening in the front wall thereof. The shell-sections of the casing have been provided with lining-sheets of sound-deadening material, such as felt; and the joints thereof, at 30 the openings or slots, through which project the keyboard and the operating levers of the machine, have been equipped with cushions or edgings, which close the same against the 35 emission of sound when the machine is in place; without, however, interfering with placement or removal of the machine, or with movement of the carriage and operating levers thereon.

40 A feature of the invention is the provision of a base-piece for the casing, and for the support of the machine; and the provision of means for quickly and effectively anchoring the casing and the machine to the base-piece.

45 Another feature of the invention is the provision of an opening in the base-piece and a pan or cover for closing the opening.

When it is desired to clean the casing of the dirt which may have accumulated from 55 erasures and other sources, the pan is removed and the dirt may be brushed out through the opening in the base.

This is a division of my application, Serial No. 590,756, filed September 27, 1922 (now 60 Patent No. 1,570,309, dated January 19, 1926).

Other features and advantages will hereinafter appear.

In the accompanying drawings, 65

Figure 1 is a view in side elevation, partly in cross-section, showing the assembled relation of the base-piece and casing with a standard therebetween and the means for holding them assembled, and showing the 70 opening in the base-piece through which the dirt may be removed.

Figure 2 is a view, in cross-sectional side elevation, showing the mounting of the casing on its base-piece. 75

Figure 3 is a top plan view of the casing, the cover being broken away to show the interior of the casing-body.

Figure 4 is a top plan view of the casing-base-piece; the same being broken away at 80 one corner to show the sound-deadening lining and supporting plate therefor.

The casing is in two principal parts, to wit, a body-portion 10 and a cover 11; the cover being hinged at 12 at the rear thereof 85 to the body-portion. The rear, front, and side walls of the casing-body are lined with sound-deadening material 13. The front wall of the casing is cut away, as at 14, so that the keyboard extension 15 of the typewriting machine 16 may protrude therethrough.

For securing the lining 13 to the sheeting 10 of the casing, the latter has, staked therein, bosses or bushings 17, which pass 95 through openings in the lining, and which are threaded to receive screws 18, which pass through retaining straps 19 laid longitudinally of the inner face of the lining, to hold the straps to the bushings 17. At its lower 100 edges the sheeting 10 has a reinforcing bead 20 formed peripherally thereon; and, from the bead 20, is turned inward to form a horizontal peripheral flange 21. The lower edge of the lining 13 is set upon the flange 21; 105 and the flange, in addition to serving as a

reinforcement, serves as a seat for the casing proper on its base-piece. At the front of the casing-body the lining 13 terminates with the sheeting 10 at the sides of the 5 opening 14 for the keyboard extension. Below the keyboard extension, the sheeting 10 is continued, from side to side of the casing, as a slightly offset strip 10^a (see Figure 1). The piece 10^a is lined with a sound-deadening strip 23 held thereto by a strap 24, which is secured by screws 18^a to bushings 17^a staked or riveted in the sheet-metal. The lining-strip 23, like the lining 13, is set upon the peripheral flange 21 of the 15 casing-body. The upper edge of the lining-strip 23 is extended, as at 23^a, as a resilient tongue to engage and press against a rod 26 on the machine when the latter is in place.

20 The casing is flared laterally upward and outward at 30, to provide room in the top thereof for movement of the platen-carriage in letter-feed and return directions.

The upper part of the casing, due to the 25 lateral flare of the side walls thereof to the usual overhangs 31, would ordinarily be wider than the platform 36 which may be the drop leaf of a drop-desk (not shown); and, if an attempt were made to set the machine at its usual elevation on the drop leaf 36, such attempt would be frustrated by engagement of the overhangs 31 of the casing with the upper corners 37 of a depression in the top of the desk (not shown), at either 30 side of the drop leaf. In order to permit the casing to clear said upper corners of the desk, and, nevertheless, to be supported upon the platform 36 located in a depression in the top of the desk, a bolster or standard 38 (see Figure 1) is interposed between the flange 21, which forms the lower edge of the casing proper, and the casing-base-piece 39. This standard includes two U-shaped sheet-metal members 40, having their ends 45 set together at 41, to form a rectangular piece. The two members 40 are held together by plates 43, which overlap the joints 41, and which are riveted, as at 44, to the U-shaped sections. Set within the channel-bars 40 are strips of sound-deadening lining-material 45, held to the bars 40 by straps 46 set upon bushings 47, staked or riveted into the members 40, and held to the bushings by screws 48 in the same manner as the 50 straps 19 are supported and held.

The base-piece 39 comprises an inverted sheet-metal pan 49, and a sheet 50 of sound-deadening material set into the same, and held therein by a plate 51, which may be 60 of wood. The plate 51 and the sheet 50 are held to the pan 49, and the pan 49 and standard 38 to the flange 21 of the casing proper, by means of screws 52, having their heads 53 set into recesses in the wooden plate 51, and passing thence upward through

the plate 51, sheet 50, pan 49 and channel-pieces 40, finally to thread into the flange 21 of the casing. Washers 52^a of sound-deadening material are set between the screw-heads 53 and the wooden plate 51. 70 The assembled casing, bolster 38 and base-piece 39 are held to the platform 36, and the machine anchored in the casing, by bolts 55, which have their heads 56 set in recesses in the bottom of the platform, and which 75 pass upward through openings 57 in the base-piece 39, through the bolster 38 and into the casing proper, where they thread at 57^a into bosses 58 on the main frame of the machine. When the bolster 38 is employed, in use of the casing on a platform in the depression of a desk, the usual short feet of the machine are replaced by longer ones 59, so that the feet may extend down 80 through the top of the pan 49, to rest upon the sound-deadening material 50, and thus have the machine at an elevation corresponding with that of the casing. For locating the machine within the casing, the pan 49 has circular, upwardly-protruding guards 90 85 95 90 turned out of the same, into which the feet 59 are placed.

If the casing is to be used on a desk without a depression, the bolster 38 is not necessary, and the casing-body may be supported directly upon the base-piece 39, as shown in Figure 2; that is to say, the flange 21 of the casing proper may be set directly upon the pan 49. The screws 52 will, in this instance, be shorter than the screws 52 shown in the Figure 1 structure; and the feet 59 of the machine will be of the ordinary height. The wooden plate 51 of the base-piece, Figures 1 and 2, is shown as having pads or feet 61, of felt or other sound-deadening material, secured thereto, by screws 62, to prevent transmission of sound-vibrations from the case to its support. 100 105

In order that the casing, or casing and standard, may be readily cleaned of dirt, from erasures and other sources, the base-piece 39 has an opening 64 therethrough, which is normally closed by a pan-like cover 65, having a peripheral flange 66, by means of which it is supported on the inverted pan 49 of the base-piece. For easy removal of the cover 65, the same is provided with a handle 67, pivoted at 68 to bosses 69 on said cover, so that the handle may normally be set down in Figure 1 position, but may be 110 115 120 swung up for removal of the cover.

As to the bolster 38 for elevating the casing for use of the same on a drop leaf, it will be noted that the same is placeable and removable, at will, between the casing-body 125 and the base-piece 39; on which latter the machine rests, whether the standard be present or not. In other words, the bolster need not be constructed to support the weight of the machine; and, in the absence 130

of necessity of provision for so supporting the machine, may be of cheaper and lighter construction than otherwise. The channel-bar cross-section of the bolster 38 gives the 5 same great rigidity against distortion.

Variations may be resorted to within the scope of the invention, and portions of the improvements may be used without others.

Having thus described my invention, I 10 claim:

1. A sound-deadening casing for a typewriting machine, comprising a body-portion, a base-piece having a hole therethrough for the removal of dirt, a door for closing the 15 hole, and means whereby the door may be opened from the interior of the casing.

2. A sound-deadening casing for a typewriting machine, having a body-portion, of sheet-material, terminating at its lower edge 20 in a horizontal, peripheral flange, and a base-piece for supporting the body-portion by said flange; the base-piece comprising a sheet-metal plate having locators struck up out of the face thereof for the feet of the 25 typewriting machine within the casing.

3. A sound-deadening casing for a typewriting machine, having a body-portion, and a base-piece comprising a plate having holes therethrough for centering the feet 30 of the machine, a sheet of sound-deadening material under the plate, and a second plate, secured to the first plate, for holding the sound-deadening material in place, and for supporting the machine.

35 4. A sound-deadening casing for a typewriting machine, having a body-portion, and a base-piece comprising an inverted pan having openings therethrough for centering the feet of the machine, a sheet of sound-deadening material within the pan, and on which the feet of the machine are adapted to rest, a plate within the pan below the sound-deadening sheet for holding the latter in place 40 for supporting the machine, and means for securing such supporting plate to the pan.

5. A sound-deadening casing for a typewriting machine, comprising a sheet-metal body terminating at its lower edge in a horizontal, peripheral flange, and a base-piece 50 comprising an inverted pan on which the casing-body is supported by said flange, and means for securing the flange to the pan; the pan having holes therethrough for bolts to anchor the machine to a platform, and hav-

ing feet or pads of sound-deadening material on the under face thereof. 55

6. The combination with a typewriting machine, of a sound-deadening base to support said machine, said base comprising an inverted pan-shaped metal portion, a sound-deadening pad held to the inside of said metal portion, and means to prevent the metal portion of said base from touching the table-top upon which said base may rest, said metal portion having holes therein through 60 which the feet of the machine may extend to rest upon the sound-deadening pad. 65

7. The combination with a typewriting machine, of a sound-deadening base to support said machine, said base comprising a 70 metal top portion, a plate, and a sound-deadening pad held between said metal top and said plate, said metal top having holes therein through which the feet of the machine may extend to rest on the sound-deadening pad. 75

8. The combination with a typewriting machine, of a sound-deadening base to support said machine, said base comprising an inverted metal pan, said pan having holes 80 therein through which the feet of the machine may extend, and a felt pad on the inside of said pan to be engaged by the feet.

9. The combination with a typewriting machine, of a sound-deadening base to support said machine, said base comprising an inverted metal pan, annular flanges pressed up from said pan to form holes into which the feet of the typewriter may be placed, a sound-subduing pad on the inside of said 90 pan for the feet to rest upon, a plate to hold the felt pad in place, and feet of sound-subduing material under said plate. 95

10. The combination with a typewriting machine, of a sound-deadening cabinet for 100 said machine, said cabinet comprising a base to support said machine, said base comprising an inverted pan-shaped metal portion, a sound-deadening pad held to the inside of said metal portion, means to prevent the metal portion of the base from touching the table upon which it may be supported, said metal portion having holes therein through which the feet of the machine may extend to rest on the sound-deadening pad, and 105 means to detachably connect the base to said cabinet.

ALFRED G. F. KUROWSKI.
